ROTARY PUMP OR MOTOR

Ferdinand M. Weyer, Detroit, Mich., assignor to
 Marine Products Company, Detroit, Mich., a
 corporation of Michigan

Application April 17, 1947, Serial No. 742,168

11 Claims. (Cl. 103—117)

1

This invention relates to fluid pressure pumps or motors.

One object of this invention is to provide a fluid pressure pump or motor having a rotor with vanes of resilient material, these vanes flexing when they engage abutments which project from the sides of the casing between the inlet and outlet ports so as to effectively separate the suction and pressure sides of the pump or motor.

Another object is to provide a fluid pressure pump or motor as set forth in the preceding object, wherein the resilient vanes are of V-shaped or herringbone cross-section, preferably extending in opposite directions from a central annular rib of resilient material.

Another object is to provide a fluid pressure pump or motor as set forth in the preceding objects, wherein the abutments consist of relatively flat-topped elevations having inclined approaches at their opposite edges so that the vanes are flexed gradually as they, in effect, climb the approaches or ramps to the top of the abutment and descend the ramp on the opposite side thereof.

Another object is to provide a fluid pressure pump or motor as set forth in the preceding objects, wherein the vanes and central annular rib are constructed of elastic deformable material such as rubber or synthetic rubber, so that the vanes possess natural resilience which holds them in sealing engagement with the walls of the abutments.

Another object is to provide a fluid pressure pump or motor as set forth in the preceding objects, wherein the vanes while traversing the top portions of the abutments give constant displacements.

Another object is to provide a modified fluid pressure pump or motor wherein the vanes are of straight rather than V-shaped or herringbone section and extend straight across the rotor in planes perpendicular to the plane of the central rib.

In the drawings:

Figure 1 is a central vertical longitudinal section through a fluid pressure pump or motor according to a preferred form of the invention;

Figure 2 is a vertical cross-section taken along the zigzag line 2—2 in Figure 1;

Figure 3 is a horizontal section, with the rotor in top-plan view, taken along the curved line 3—3 in Figure 2, showing the flexing of the rotor vanes against the abutments;

Figure 4 is a top-plan view of the rotor shown in Figure 3, removed from the casing;

Figure 5 is a side elevation of one of the abut-

2

ment plates shown in Figure 3, removed from the pump or motor;

Figure 6 is an edge elevation of the abutment plates;

Figure 7 is a top-plan view of a modified rotor, removed from the pump or motor;

Figure 8 is a side elevation of the modified rotor shown in Figure 7; and

Figure 9 is a central vertical longitudinal section through a further modified pump or motor according to the invention.

Referring to the drawings in detail, Figure 1 shows a fluid pressure pump or motor generally designated 10 according to a preferred form of

15 the invention and including a base 11 with a central pedestal 12 having a horizontal bore 13 therein. Radiating outward from the central pedestal 12 which forms a journal bearing for a shaft 14, is a cup-shaped housing portion 15.

20 The housing portion 15 consists of a disc-like radial wall 16 and a cylindrical axial wall 17 having a cylindrical bore or chamber 18 therein, closed by a disc-like end plate 19 bolted thereto as at 20. The end plate 19 is provided with a 25 reduced diameter portion 21 which extends into the cylindrical chamber 18.

Mounted in the cylindrical chamber 18 on opposite sides thereof are oppositely-facing abutment discs or plates 22 of similar but opposite construction and having projections 23 thereon

30 facing outward in opposite directions and seated in recesses 24 in the wall portion 16 and end plate 19 respectively (Figure 1). The abutment discs or plates 22 (Figures 5 and 6) are circular with central holes 25 and having offset abutment 35 portions 26 approached by inclined portions 27 forming ramps leading to the flat-topped middle portion 28 thereof. Thus, the abutment portions 26 are approximately fan-shaped with the central portions 29 cut away along an arc so as 40 to provide a flat surface surrounding the central hole 25.

The abutment discs or plates 22 are mounted in the housing portion 15 between radially extending ports 30 and 31 respectively (Figure 2) 45 formed in radially-extending bosses 32 and 33 with threaded openings 34 and 35 to which the intake and discharge pipes are connected.

Mounted on the inner end of the shaft 14 and splined thereto as at 36 (Figure 1) is a rotor 37. The rotor 37 consists of an annular sleeve 38 which is bored and grooved to fit the splines 36, and which has an annular ridge or flange 39 running around the central portion thereof. Mounted upon the sleeve 38, which is preferably

50 55 of metal, is the hub 40 of the vane unit 41, which

is formed of elastic deformable material such as rubber or synthetic rubber. The vane unit 41 has a central disc-shaped rib 42 projecting outward from the hub 40, and the rib 42 carries radially extending vanes 43 also of elastic deformable material (Figure 4). The vanes 43 are preferably arranged in approximately V-shaped or herringbone formations on opposite sides of the rib 42 and are cut away as at 44 (Figure 1) where the disc-shaped rib 42 joins the hub 40. The gaps 44 between the vanes 43 and the hub 40 provide flexibility for the flexing of the vanes 43 as they pass over the abutment projections 26 (Figure 3). The vanes 43 are so inclined relatively to the disc-shaped rib 41 that their ends resemble arrow heads aimed in the direction of rotation of the rotor. The end portions 45 of the hub 40 project outward upon the ends of the vanes 43 (Figure 4), and also have annular grooves 46 therein engaging the side walls of the abutment discs or plates 22.

Leading into the bore 13 is a transverse threaded hole or port 47 (Figure 1), into which is threaded the stem 48 of an oil cup 49. The latter is of a conventional pattern, having a lid 50 pivoted thereto at 51 so as to permit the insertion of oil or other lubricant for lubricating the shaft 14. The right-hand end of the bore 13 is provided with an annular cavity 52 containing annular packing 53 and compressed by an annular gland or nut 54 threaded therein as at 55. This backing 53 prevents the loss of the lubricant along the shaft 14.

Mounted on the outer end of the shaft 14 and secured thereto as by the set-screw 56, is the hub 57 of a pulley 58 which is provided with a suitable annular groove 59 for engagement by a driving belt (not shown). The pulley 58 is a conventional type and for purposes of convenience, is shown as having a V-groove to accommodate a V-belt. It will be evident, however, that any other type of belt or sprocket may be used in order to drive the shaft 14.

In the operation of the principal form of the invention shown in Figures 1 to 6 inclusive, the pump or motor is assembled as shown in Figures 1 and 2, and power is applied to the driving pulley 58, the rotation of the rotor 37 causes its herringbone vanes to be flexed slightly inward as they engage the side walls of the abutment discs 22. The vanes 43 are flexed still further inward as they climb the ramp 27 and pass over the flat middle portion 28 between the ports 30 and 31. Consequently, with a counter-clockwise rotation of the shaft 14 (Figure 2), as the vanes 43 flex inward while climbing the ramps 27 adjacent the port 31, they squeeze water out of the space between the opposite "arms" of the V-shaped vanes. This water, having nowhere else to go because of the incompressibility of the water behind it, is forced out through the port 31. On the other hand, when the vanes 43 expand on leaving the ramps 27 adjacent the port 30, they suck in water. Therefore, the port 30 becomes the suction or intake port and the port 31 the pressure or discharge port. Thus, the pressure fluid developed by the rotation of the rotor 37 is expelled through the discharge port 31 and is carried away by the discharge conduit (not shown). If the pump is used for a bilge pump, then the suction port 30 is connected to the bilges of the boat and the discharge port 31 to the over-board line. From experience it has been found that the pump shown in Figures 1 to 6 inclusive is very quiet in operation and develops an unusually high oper-

ating pressure. The pump is simple in construction, inexpensive to manufacture, and of long operating life.

The operation of the preferred form of the invention shown in Figures 1 to 6 inclusive has been described as that of a pump. It will be understood, however, that by feeding pressure fluid to the port 30 and allowing it to discharge from the port 31, the device will operate as a motor to rotate the shaft 14 and pulley 58. Power can then be taken off by means of a belt engaging the pulley groove 59.

The modified rotor 60 shown in Figures 7 and 8 is generally similar to the principal form of rotor 37 shown in Figures 1 to 4 inclusive, and has a similar central sleeve 61 upon which is mounted the hub 62 of a rotor unit 63 of elastic deformable material, such as rubber or synthetic rubber. The rotor 60 is also provided with a central disc-shaped rib 64 with vanes 65 arranged in planes which are substantially perpendicular to the plane of the rib 64 instead of being inclined at an angle thereto, as in the principal form of the invention. The vanes 65, like the vanes 43, are cut away so as to provide caps 66 adjacent the hub 62, this construction permitting free flexing of the vanes 65. The remainder of the rotor 60 is substantially of the same construction as that of the rotor 37, and its operation is similar. The rotor 60, however, is capable of rotating in opposite directions, whereas the rotor 37 is preferably adapted to rotate in one direction only. The ends of the vanes 65, of course, flex inward as they engage the abutment portions 26 of the abutment discs or plates 22 and straighten out when they pass beyond the portion 26.

The modified pump or motor 70 shown in Figure 9 employs a rotor 37 similar to the rotor 37 employed in the pump or motor of Figures 1 to 6 inclusive and having its various parts similarly designated. The rotor 37, however, is mounted in a casing 71 having a chamber 72 with a substantially cylindrical peripheral wall 73 having inlet and exhaust ports therein similar to the ports 34 and 35 shown in Figure 2. The chamber 72 is closed by an end plate 74 which has an end wall 75 inclined at slightly less than right angles to the axis of the rotor shaft 14. The chamber 72 has an end wall 76 inclined at slightly less than right angles to the axis of the rotor shaft 14 so that the end walls 75 and 76 are slightly closer together at the top of the chamber 72 than at the bottom thereof. Thus the end walls 75 and 76 are inclined to the axis of rotation of the shaft 14 at an angle of slightly less than 90°.

The modified pump or motor 70 does not employ the abutments 26 used in the form shown in Figures 1 to 6 inclusive, but the inclined end walls 75 and 76 themselves serve as abutments. The shaft 14 is journaled in a bore 77 in the casing 71 in a manner similar to that shown in Figure 1 and driven in a similar way. The end plate 74 is also secured to the casing 71 in a similar manner to that of Figure 1.

The operation of the modified pump or motor shown in Figure 9 is generally similar to that of the form of pump or motor shown in Figures 1 to 6 inclusive. In its operation as a pump, power is applied to rotate the shaft 14 and consequently the rotor 37. As the vanes 43 pass from the bottom of the casing 71 to the top thereof, the converging of the end walls 75 and

16 causes the vanes 43 to flex inward in an axial direction, thereby bringing about a pumping action with respect to the liquid in the chamber 72 and causing liquid to be drawn in through the inlet port and out through the exhaust port in a manner similar to the operation of the pump or motor 10 shown in Figures 1 to 6 inclusive.

The operation of the pump or motor 10 as a motor is brought about by supplying pressure fluid to one of the ports, this causing the rotor 37 to rotate and impart rotation to the shaft 14 before being discharged through the outlet port. The vanes 43 flex laterally as before as they pass from the bottom of the chamber 72 to the top thereof, because of the converging of the end walls 15 and 16.

While the intake and discharge ports 30 and 31 have been described as circumferentially spaced, they are not necessarily located entirely on the peripheral portion 17, but may extend partially down into the side walls or be located in the side walls 16 and 19 adjacent the periphery. This construction is employed in high-speed installations where the centrifugal force arising from the rotating liquid becomes unduly great.

What I claim is:

1. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said vanes at their inner ends being cut away from said hub portion.

2. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said vanes being arranged in approximately V-shaped formations, said vanes at their inner ends being cut away from said hub portion.

3. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction

approximately parallel to the axis of rotation of said rotor, and said vanes projecting in opposite directions from said flange portion and at oblique angles relatively thereto, said vanes at their inner ends being cut away from said hub portion.

4. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said flange portion projecting outward from said hub portion at a location intermediate the ends thereof, and said vanes being secured to said flange portion at oblique angles relatively thereto, said vanes at their inner ends being cut away from said hub portion.

5. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said vanes being arranged in approximately V-shaped formations, said vanes at their inner ends being cut away from said hub portion.

6. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said flange portion projecting outward from said hub portion at a location intermediate the ends thereof, and said vanes being secured to said flange portion at oblique angles relatively thereto, said vanes at their inner ends being cut away from said hub portion.

7. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment

mounted on and projecting axially inward from each of said end walls between said ports and engageable with said vanes to flex said vanes during rotation of said rotor in a direction approximately parallel to the axis of rotation of said rotor, said abutment having a central portion with a substantially flat abutment surface and inclined portions leading from locations near said ports to said central portion, said vanes at their inner ends being cut away from said hub portion.

8. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and an abutment mounted on and projecting axially inward from each of said end walls between said ports and engageable with said vanes to flex said vanes during rotation of said rotor in a direction approximately parallel to the axis of rotation of said rotor, said abutment having its opposite ends substantially flush with said end walls adjacent said ports and projecting axially therefrom in inclined planes, said abutment having a central portion with a substantially flat abutment surface substantially parallel with said end wall and spaced axially therefrom, said vanes at their inner ends being cut away from said hub portion.

9. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange portion projecting from said hub portion, said flange portion having vanes of elastic deformable material secured thereto and disposed radially relatively to said hub portion, and a pair of inwardly and axially projecting abutments mounted on said end walls between said ports and engageable with said vanes to flex said vanes during rotation of said rotor, one of said abutments being mounted on each of said end walls, said abutments having substantially flat central portions and inclined end portions leading thereto, said vanes at their inner ends being cut away from said hub portion.

10. A rotary pump or motor comprising a hollow casing having axially-spaced end walls and circumferentially-spaced fluid intake and discharge ports, a shaft rotatably mounted in said casing, a rotor having a hub portion mounted on said shaft, said rotor also having a flange

portion projecting from said hub portion, said flange portion having vanes of elastic deformable material secured thereto and disposed radially relatively to said hub portion, and an abutment

5 mounted on and projecting axially inward from each of said end walls between said ports and engageable with said vanes to flex said vanes during rotation of said rotor in a direction approximately parallel to the axis of rotation of said rotor, said vanes being disposed substantially in axial planes of said shaft and substantially perpendicular to said flange portion, said vanes at their inner ends being cut away from said hub portion.

15 11. A rotary pump or motor comprising a hollow casing having axially-spaced end walls and circumferentially-spaced fluid intake and discharge ports, a shaft rotatably mounted in said casing, a rotor having a hub portion mounted

20 on said shaft, said rotor also having a flange portion projecting from said hub portion, said flange portion having vanes of elastic deformable material secured thereto and disposed radially relatively to said hub portion, and an abutment

25 mounted on and projecting axially inward from each of said end walls between said ports and engageable with said vanes to flex said vanes during rotation of said rotor in a direction approximately parallel to the axis of rotation of said rotor, said flange portion projecting outward from said hub portion intermediate its ends, and said vanes projecting axially in opposite directions from said flange portion in substantially axial directions and substantially perpendicular

30 to said flange portion, said vanes at their inner ends being cut away from said hub portion.
